DESIGN FOR A VENTILATOR CASING

Walter H. Kirchheim, Mount Vernon, and Frank C. Reynolds, New York, N. Y., assignors to American Radiator Company, New York, N. Y., a corporation of New Jersey

Application September 21, 1935, Serial No. 58,646

Term of patent 14 years

To all whom it may concern:

Be it known that we, Walter H. Kirchheim and Frank C. Reynolds, both citizens of the United States, residing, respectively, at Mount Vernon, in the county of Westchester and State of New York, and New York, in the county of New York and State of New York, have invented a new, original, and ornamental Design for a Ventilator Casing, of which the following is a specification, reference being had to the accompanying drawing, forming part thereof.

In said drawing--

Figure 1 is a view in perspective of a ventilator casing embodying our new design, and

Figure 2 is a front elevational view thereof.

We claim:

The ornamental design for a ventilator casing, as shown.

In witness whereof, I, Walter H. Kirchheim, have hereunto subscribed my name.

WALTER H. KIRCHHEIM.

In witness whereof, I, Frank C. Reynolds, have hereunto subscribed my name.

FRANK C. REYNOLDS.
